(57) CLAIM

The ornamental design for the housing for a ceiling fan, as shown and described.

DESCRIPTION

FIG. 1 is a bottom plan view of the housing for a ceiling fan in accordance with my design;

FIG. 2 is an enlarged front view of the housing for a ceiling fan in accordance with my design;

FIG. 3 is an enlarged top plan view taken along line 3—3 in FIG. 2; and,

FIG. 4 is an enlarged bottom plan view of the housing for a ceiling fan in accordance with my design.

The front and rear, left and right elevational views are symmetrical.

The broken line showing of environmental structure in FIGS. 1-3 is for illustrative purposes only and forms no part of the claimed design.
